D5416

UNITED STATES PATENT OFFICE.

JAMES L. JACKSON, OF NEW YORK, N. Y.

DESIGN FOR HOOKS FOR HANGING HARNESS ON.

Specification forming part of Design No. 5,416, dated December 12, 1871.

To all whom it may concern:

Be it known that I, JAMES L. JACKSON, of the city and State of New York, have invented or produced a new and original Design for Hooks for Harness, &c.; and the following is declared to be a correct description of the same.

This design relates to the ornamental bracket which supports the hooks.

In the drawing the said bracket and hooks are shown by a perspective view.

The back plate *a* is provided with hooks *b b*, the top hook being the longest and the bottom hook the shortest. The brackets *c* are of the ornamental shape represented in the drawing,

with a half arch and circular and semicircular ornaments.

The sizes of the brackets are to be graduated to correspond with the size of the hooks, as illustrated in the drawing.

I claim—

The design of the hook for harness, substantially as shown and described.

Signed by me this 13th day of July, A. D. 1871.
JAMES L. JACKSON.

Witnesses:

HAROLD SERRELL,
GEO. T. PINCKNEY.
